(57) **CLAIM**

The ornamental design for a digital video camera, as shown and described.

DESCRIPTION

FIG. 1 is a front view of a digital video camera;
FIG. 2 is a rear view of the digital video camera;
FIG. 3 is a right side view of the digital video camera;
FIG. 4 is a left side view of the digital video camera;
FIG. 5 is a bottom view of the digital video camera;
FIG. 6 is a top view of the digital video camera;
FIG. 7 is a front perspective view of the digital video camera;
FIG. 8 is a rear perspective view of the digital video camera;
FIG. 9 is an enlarged view of the indicated area "9" in FIG. 1;
FIG. 10 is an enlarged view of the indicated area "10" in FIG. 1;
FIG. 11 is an enlarged view of the indicated area "11" in FIG. 2;
FIG. 12 is an enlarged view of the indicated area "12" in FIG. 2;
FIG. 13 is an enlarged view of the indicated area "13" in FIG. 4;
FIG. 14 is an enlarged view of the indicated area "14" in FIG. 5;
FIG. 15 is an enlarged view of the indicated area "15" in FIG. 6; and,
FIG. 16 is an enlarged view of the indicated area "16" in FIG. 6.
The broken lines depict portions of the digital video camera in which the design is embodied that form no part of the claimed design. The dot-dash broken lines indicating an enlargement portion of the design form no part of the claimed design.
